UNITED STATES PATENT OFFICE.

LIBERTY WALKUP, OF ROCKFORD, ILLINOIS.

PAINT-DISTRIBUTER.

SPECIFICATION forming part of Letters Patent No. 298,138, dated May 6, 1884.

Application filed September 10, 1883. (Model.)

To all whom it may concern:

Be it known that I, LIBERTY WALKUP, a citizen of the United States, residing in the city of Rockford, in the county of Winnebago 5 and State of Illinois, have invented a new and useful Improvement in Paint-Distributers, of which the following is a specification.

This invention relates to machines employed in the distribution of pigments in the art of 10 painting, but more especially in the fine arts.

The object of this invention is to produce a more efficient machine of its class in a more 15 convenient and practical form; and it consists in the novel construction and arrangement of the parts, and in the mechanism employed as embodied in the accompanying drawings, all of which will be hereinafter more fully described.

In the accompanying drawings, Figure 1 is 20 a plan view of a machine embodying my invention, and in which the operative parts are in their central position in the case. Fig. 2 is an under face view thereof. Fig. 3 is a plan view with the cover removed, and in which 25 the operative parts are in their forward position. Fig. 4 is also a plan view with the cover removed, and in which the operative parts are in their rear position. Fig. 5 is a front edge view. Fig. 6 is a front end view, in which the 30 vertical air-tube and the pigment-receptacle are shown in central section. Fig. 7 is a vertical central section of the wind-wheel and walking-beam. Fig. 8 is an isometrical representation of the operative parts removed 35 from the case; and Fig. 9 is an under face isometrical representation of the removed cover.

In the several figures of the accompanying 40 drawings like parts are designated by like letters of reference, and in this instance the working parts of my improved machine are mainly 45 inclosed in a hand-piece of case form. This hand-piece is composed of a bottom, A, and vertical edges B, in this instance of plate material produced in the box form represented, 50 having its forward end portion, A', inclined rearward, and oblique or inclined to the horizontal plane of the handle portion, having its rear edge, A², on a higher plane. This forward inclined end portion is provided with a lid or cover, C, made removable, or having a hinged connection with the upper edge of its

rear vertical wall in a manner to permit it to open rearward to expose the working parts located within the forward section of the case. This hinged cover is provided toward its forward end with a crystal, a, through which the movement may be seen without opening the cover. The handle portion of this case is provided with a cap, D, having a detachable or hinged connection with the vertical side walls 55 thereof. The removal of this cap, in connection with the hinged cover when open, serves to expose the working parts contained within the case.

At E is represented a wind-wheel support, 60 of bed-plate form, on which to support the main working parts of the machine. This bed-plate is placed in the forward end of the case, and is connected to the bottom thereof by means of screws b, passed through oblique 65 slots b', formed in the bottom of the case, and screw-threaded into the bed-plate in such a manner as to permit the plate to move endwise in the case in the direction of the slot-openings.

At b" is represented a spring-washer, placed 70 under the head of one of the screws b, on the outer side of the bottom plate of the case, to regulate the friction of the bed-plate on the bottom thereof.

At F is represented a wind-wheel composed 75 of two annular rings of disk form, suitably separated, and provided at proper intervals, in the form of an overshot water-wheel, with buckets to receive an air-jet, to cause it to revolve on its journal-supports. This wheel is supported on a crank-shaft, c, to revolve in a suitable foot-bearing in the bed-plate and in an adjustable screw-bearing in the free end of the overhanging arm c', rising from the bed-plate and overhanging the wheel on its upper 80 side.

At d is represented a vertical shaft, supported 85 to oscillate in a foot-bearing in the bed-plate and in an adjustable screw-bearing in the free end of the overhanging arm d', rising from the bed-plate and overhanging the upper end of the shaft.

At e is represented a walking-beam fixed to 90 the vertical shaft d, to oscillate with the shaft. 95 Both arms of this walking-beam are slotted lengthwise, and its rear slotted arm extends 100

over the wind-wheel and receives the wrist of the crank-shaft *c* thereof. The forward slotted arm of the walking-beam extends through a slot, *e*', formed in the forward vertical end wall 15 thereof, and immediately outside of the case receives the wrist or downturned end of the needle *h*.

At *h*' is represented a guard-plate fixed to the forward vertical end wall of the case in the plane of the lower wall of the slot *e*', from which it extends forward to protect the forward free end of the walking-beam projecting from the case over the plate. The vertical arm *h*' of this plate extends lengthwise of the vertical end wall, and its inner face is reduced to form a vertical slot, *i*, between it and the vertical end wall of the case. This vertical slot *i* secures the wrist or inner end of the downturned arm of the needle *h*, depending through the slot-slotted free arm of the walking-beam, in such a manner as to permit a free reciprocating movement of the needle in the direction of its length.

At *H* is represented a pigment-receptacle—25 in this instance of spoon form—provided with an arm, *h*, extending rearward on the front edge of the case, having a pivotal connection therewith at *h*' in a manner to permit its spoon portion to swing downward from the case. The rear edge of the spoon portion is provided 30 with a lip-extension, (represented in dotted lines at *h*''), designed to engage an indentation in the edge portion of the case, to hold the spoon in connection therewith in a detachable manner, and in position thereon to receive the needle in its angle center.

At *l* is represented a finger, pivoted at one end to the vertical end wall of the case, and capable of a swinging movement in the vertical plane of the needle, and having its free end forked to engage the needle when in its downturned position, to hold it in the center of the receptacle to give direction to its reciprocating movements.

At *L* is represented an air-tube, supported on the bed-plate in such position relatively with wind-wheel that a current of air forced through its nozzle end will be delivered onto the buckets of the wind-wheel to cause it to 50 revolve. This air-tube is fitted with a single-way check-valve, *l*', to regulate the flow of air through the tube to the wind-wheel. This valve is fitted with a lever-arm, *l*'', projecting laterally from its upper end, having its free 55 end portion extending through a suitable opening in the free end of an arm, *l*''', fixed to the rear vertical wall of the case in a manner to permit of an adjustment in the lengthwise direction thereof. This connection of the valve 60 with the arm *l*''' is such that the back-and-forth movement of the bed-plate within the case operates automatically to change the valve to vary the quantity of air delivered on the wheel, and by means of the adjustable arm *l*''' the 65 movement of the valve may be so changed as to vary the quantity of air delivered at differ-

ent points in the back-and-forth movement of the bed-plate. This air-tube *L* is connected with a branch tube, *m*, by means of a flexible tube, *K*, in a manner not to interfere with the 70 back-and-forth movement of the bed-plate.

At *L* is represented the main tube, a portion of which extends rearward through the case, and is designed to connect with the air-supply. The branch tube *m* connects with this main 75 tube within the case, and receives the rear end of the flexible tube *K*.

At *M* is represented a branch of the main air-tube, which extends forward in the case and outward through the front edge thereof 80 near its forward end, and its outer end is fitted with a vertical nozzle, *n*, opening centrally over the needle in front of the pigment-receptacle. The rear end portion, *n*', of the main tube, extending through the rear end of the 85 case, is fitted in valve-seat form, as represented at *n*''', consisting of a prominence projecting inward from one side of the tube, and an external opening on the opposite side thereof centrally over the prominence. This projecting end portion of the main tube is provided with a flexible tube, *n*''', which extends over the external side opening in such a manner that when pressed into the side opening of the tube it will engage the prominence projecting 95 inward from its opposite side, and close the passage and cut off the flow of air through the tube. The extreme outer end portion of the main air-tube *L* receives the end portion of a flexible tube, *P*, designed to connect with the 100 air-supply.

At *R* is represented a valve-lever placed within the case, having a pivotal connection at *o* with the bottom thereof. The rear end 105 of this valve-lever extends outward through the rear end of the case, and its projecting end, at *o*', is fitted to engage the flexible tube *n*''' over the side opening in the main air-tube *L* to press it against the prominence in the tube to close the passage.

At *p* is represented a spring having a connection with the valve-lever and with the case, operating to hold the valve-lever to the valve-seat.

At *T* is represented a thumb lever, of a 115 suitable conformation, extending through the front side of the case, which is slotted to receive it in a manner to permit of a back-and-forth movement of its free end in the lengthwise direction of the case. The inner end of this thumb-lever is pivoted at *p*' to the forward end of the valve-lever in such a manner that its inward endwise movement will counteract the force of the spring *p* and open the valve.

At *t* is represented a connecting-link, having a pivotal connection of one end, at *t*', with the bed-plate *E* and a pivotal connection of its other end, at *t*'', with the thumb-lever *T* near the center of its length, by which the backward and forward movement of the free end of the thumb-lever will impart an endwise

back-and-forth movement of the bed-plate and of the several parts mounted thereon.

At *u* is represented a thumb-screw, having a screw-thread connection with the case at its forward end, in such position that its inner end will engage the bed-plate to limit its forward movement. By means of this thumb-screw the forward movement of the bed-plate may be regulated to limit it at any point within 10 the limits of the devices.

At *u'* is represented a rod fixed to the front edge of the case, and extending forward thereof in position to be received in the left hand of the operator, to enable him to control the 15 movements of the machine with greater certainty.

In the use of my improved paint-distributer, the main air-tube is connected with the air-supply. The pigment, in liquid form of a 20 proper consistency, is then placed in the receptacle *H*. The valve *o'* is then lifted from its seat by depressing the thumb-lever *T*, which permits a flow of air, under pressure, to pass through the branch pipe *I* and impinge upon the buckets of the wind-wheel, 25 causing it to revolve rapidly, and by reason of its crank and walking-beam connection will impart a rapid endwise-reciprocating movement to the needle connected with the walking-beam. In this movement the needle, 30 through the pigment contained in the receptacle, will, in its outward throws, carry with it a quantity of the pigment under the air-jet delivered from the vertical nozzle *n*, which 35 jet of air will disengage the pigment from the projecting end of the needle and deliver it in finely-divided particles or spray to any surface a proper distance below the needle. The quantity of pigment delivered at each outward throw of the needle and the character 40 of work of which the machine is capable are dependent, mainly, upon the rapidity of the vibrations of the needle and the length of its throws. These, for the various kinds of work 45 to which the machine is adapted, require that they be under the control of the operator, to be used at any point within the capacity of the devices. This I accomplish in my improved machine by means of the thumb-lever 50 and its connection with the working parts, from which it will be seen that with the thumb-lever in its rearward depressed position, as shown in Fig. 4, the check-valve *t'* will be open to its greatest capacity to impart to the wheel 55 its greatest velocity, and the relative position of the wheel to the needle will be such as to impart to the needle its greatest throw and give to the machine its greatest capacity for the distribution of the largest quantity of the pigment. 60 When the thumb-lever is in its forward position, as shown in Fig. 3, if depressed to open the valve in the main tube, the check-valve *t'* will be in position to deliver the smallest quantity of air to the wheel, to cause 65 it to revolve at its lowest velocity; and the relative position of the wheel with the needle

will be such as to impart to the needle its shortest throw and reduce the capacity of the machine for the distribution of the pigment to its lowest point. Between these extremes the 70 machine, by means of the thumb-lever, is under the complete control of the operator, to regulate the distribution of the pigments as the character of the work may require in the judgment of the operator. 75

I claim as my invention—

1. In a paint-distributer, the herein-described case, consisting of a hand portion provided with a hinged or removable cover, and a forward end portion oblique to the hand portion, having a rearward inclination lengthwise and an upward lateral inclination from its front edge rearward, said inclined portion provided with a removable or hinged lid, substantially as and for the purpose set forth. 80

2. In a paint-distributer, the combination, with the case for containing the operative parts, of a support for said parts, mounted in the case in such manner as to permit an endwise movement thereof, substantially as and 90 for the purpose set forth.

3. In a paint-distributer, the combination, with a wind-wheel support capable of an endwise movement relatively with its support, of a wind-wheel mounted upon the movable support and capable of revolving on pivotal bearings, substantially as and for the purpose set forth. 95

4. In a paint-distributer, the combination, with a wind-wheel support capable of an endwise movement, and a wind-wheel mounted to revolve in bearing-supports thereon, of a walking-beam mounted to oscillate in bearing-supports on the wind-wheel support, and having a wrist-connection with the wind-wheel, substantially as and for the purpose set forth. 100

5. In a paint-distributer, the combination, with a walking-beam capable of an endwise movement, of a needle having a wrist-connection with the walking-beam, and capable of a reciprocating movement in the direction of its length of varying throws, substantially as and for the purpose set forth. 110

6. In a paint-distributer, the combination, with the case containing the operative parts, and with a walking-beam to impart motion to the needle, of a guard-plate to protect the projecting arm of the walking-beam, substantially as set forth. 115

7. In a paint-distributer, the combination, with a needle having a wrist-connection with the walking-beam, of a slotted guide to receive the depending wrist of the needle, substantially as and for the purpose set forth. 120

8. In a paint-distributer, the combination, with a needle supported to reciprocate in a pigment-receptacle, and having a wrist-connection with a walking-beam and with a guide-slot, of a guide-finger to engage the needle, 130 said finger having a pivotal support to permit of a swinging movement in the vertical plane

of the needle, substantially as and for the purpose set forth.

9. In a paint-distributer, the pigment-receptacle having a pivotal connection with the case, and a lip projecting from the inner edge of the receptacle to engage a corresponding indentation in the case, for holding the pigment-receptacle at a fixed point, substantially as and for the purpose set forth.

10. In a paint-distributer, the combination, with a wind-wheel and with its movable support, of an air-tube mounted upon the wind-wheel support, substantially as and for the purpose set forth.

11. In a paint-distributer, the combination, with the main air-tube and with the branch tube mounted upon the adjustable wind-wheel support, of a flexible tube to connect the branch with the main air-tube, substantially as and for the purpose set forth.

12. In a paint-distributer, the combination, with the spring-actuated valve-lever, of a thumb-lever having a pivotal connection with the free end of the valve-lever, substantially as and for the purpose set forth.

13. In a paint-distributer, the combination, with the wind-wheel support and with the adjustable thumb-lever, of a connecting-link hav-

ing a pivotal connection with the wheel-support and with the thumb-lever, substantially as and for the purpose set forth.

14. In a paint-distributer, the combination, with the check-valve in the air-tube, mounted upon the wind-wheel support, and with a perforated arm having an adjustable support, of a lever fixed to the check-valve, and having its free end engage the perforated arm, substantially as and for the purpose set forth.

15. In a paint-distributer, the combination, with a reciprocating needle, a walking-beam, and a wind-wheel, of a thumb-lever and a link-connection with the thumb-lever and with the wind-wheel and walking-beam support, substantially as and for the purpose set forth.

16. In a paint-distributer, the herein-described combination of a wind-wheel mounted on a movable support, a valve to control the flow of air through the main supply-tube, a thumb-lever, and a link connecting the valve-lever and movable support of the wheel, substantially as and for the purpose set forth.

LIBERTY WALKUP.
